UNITED STATES PATENT OFFICE.

WILLIAM MARTINDALE, OF ALLISTON, CANADA.

SAFETY-HOOK.

SPECIFICATION forming part of Letters Patent No. 630,064, dated August 1, 1899.

Application filed February 10, 1899. Serial No. 705,218. (No model.)

To all whom it may concern:

Be it known that I, WILLIAM MARTINDALE, a subject of Her Majesty the Queen of Great Britain, residing at Alliston, county of Simcoe, Province of Ontario, Canada, have invented certain new and useful Improvements in Safety-Hooks; and I do hereby declare that the following is a full, clear, and exact description of the invention, such as will enable others skilled in the art to which it appertains to make and use the same.

My invention relates to improvements in safety-hooks.

The object of my invention is to provide a safety-hook in which the use of a spring is obviated, in which the parts are held in positive position when locked, and which can only be opened by a pivotal movement of one of the members.

A further object is to provide a construction which is neat and attractive in appearance, durable in construction, simple and efficient in operation, and which can be made at a small cost of manufacture.

To these and other ends my invention consists in the improved construction and combination of parts hereinafter fully described, and particularly pointed out in the appended claims.

In the drawings, in which similar numerals of reference indicate similar parts in all of the views, Figure 1 is a perspective view of my safety-hook in operative position. Fig. 2 is a similar view of the hook in its open position.

Figs. 3, 4, and 5 are detail views of the parts.

Snap-hooks have generally been found with the snap portion either a spring or spring-operated. As a spring is liable to become twisted, &c., allowing the parts to become of no value unless new springs are inserted, such construction is disadvantageous. Another disadvantage consists in that the snap portion must be operated positively, which in cold weather is very inconvenient. To obviate these and other disadvantages, I have provided a construction in which the use of a spring is eliminated, the safety portion being held in positive contact with the hook portion by the pivotally-mounted member of the hook, being released only upon passing said pivotal member to a predetermined position.

1 designates the hook portion, formed sub-

stantially as shown in Fig. 4, having its rear portion 2 formed with a rounded head, the face 3 being flat. A recess 4 is formed in the portion 2, said recess being enlarged laterally, as shown at 5, said recess being adapted to receive the rear end of the safety portion 6, the rear end of which is provided with laterally-extending lugs 7, adapted to rest within the enlarged portion of the recess, as shown in dotted lines in Fig. 4. The front end of the safety portion is adapted to fit within a suitable recess 8, formed on the front end of the hook portion 1, the end of the safety portion 6 being arranged to fit said recess.

9 designates the pivotally-mounted member, formed substantially as shown in Fig. 3, said member having a rounded portion 10 and face 11, adapted to fit the rounded head and the face 3 of the portion 1. The portion 10 is provided with a radial opening 12 at one side, said opening allowing of the opening of the safety-hook, as hereinafter set forth. The member 9 is also provided with a strap-connecting portion 13.

The members are assembled by the placing of the safety portion in position and then placing the pivotal member on the head of the member 1 and then connecting said member and the hook portion by a rivet 14, passed centrally through the rounded portions hereinafter described.

The operation of the device is exceedingly simple, it being apparent that when the member 9 is in the position shown in Fig. 1 or any other position excepting that shown in Fig. 2 the safety portion will be held positively in its closed position. To open the hook, it is necessary only to move the member 9 to the position shown in Fig. 2, whereupon the safety portion may be moved outwardly away from the hook portion.

It will be readily seen that to remove a ring, &c., from the hook it will not be necessary to manipulate any spring portion, the strap being grasped and drawn to one side, rotating the member 9 on its pivot and freeing the safety portion.

The advantages of this construction are many; but inasmuch as they are obviously apparent it is not thought necessary to point them out in detail.

While I have herein shown a preferred form

of carrying my invention into effect, yet I do not desire to limit myself to such preferred details of construction, but claim the right to use any and all modifications thereof which 5 will serve to carry into effect the objects to be attained by this invention in so far as such modifications and changes may fall within the spirit and scope of my said invention.

Having thus described my invention, what 10 I claim as new is—

1. A safety-hook, comprising a hook member having a slot in its upper portion, a safety member removably pivoted in said slot, and a strap member pivotally secured to said hook member and covering said slot, said strap member controlling the movement of said safety member, substantially as described.
- 15

2. A safety-hook, comprising a hook member having a slot in its upper portion, a safety member removably pivoted in said slot, and a strap member pivotally secured to said hook member and engaging the safety member with its lower edge thereby locking the same, said strap member having a radial recess adapted to be brought into alignment with 25 said slot for releasing said safety member, substantially as described.

In witness whereof I have hereunto set my hand in the presence of two witnesses.

WILLIAM MARTINDALE.
